AUTOMATIC PHONOGRAPH

Mahlon W. Kenney, Oak Park, Ill., assignor to
 J. P. Seeburg Corporation, Chicago, Ill., a cor-
 poration of Illinois

Application November 4, 1944, Serial No. 561,987

18 Claims. (Cl. 177—353)

This invention relates to automatic phonographs and particularly to multiselective automatic phonographs having a plurality of recordings available for selections by the operator.

One of the objects of the present invention is to provide an improved multiselective phonograph in which the operator can select a plurality of recordings to be reproduced in the order in which the selection is made.

In copending application Ser. No. 524,232, filed February 28, 1944, by Mahlon W. Kenney and Hugh H. Davis, there is described and claimed a chronologically selective phonograph having an elongated member such as a tape upon which a plurality of selections are stored in the form of perforations made in the longitudinal direction of the tape. The number of perforations is individual to each selection. In the machine of the application referred to each selection consisted of two separate trains of perforations. In the normal operation of that machine a plurality of selecting signals were applied to the tape and the phonograph was put into operation to take the signals from the tape and to play the corresponding recordings in their order on the tape. After the reproduction of each recording, another signal was taken from the tape and so forth until all selections were taken from the tape and the corresponding recordings reproduced. The matter of storing the portion of the tape carrying a large number of signals presents considerable difficulty when a large program is preselected.

The principal object of the present invention is to provide a phonograph in which the signals are recorded upon a broad tape in the transverse direction of the tape so that a large number of selecting signals may be accommodated in a relatively short length of tape, obviating the difficulties presented by the narrow tape in which the signals are applied in the longitudinal direction of the tape.

Other objects, advantages, and capabilities of the invention will appear from the following description of a preferred embodiment thereof taken in conjunction with the accompanying drawings, in which

Fig. 1 is a diagrammatic view and wiring diagram of the phonograph;

Fig. 2 is a perspective view of the signal printing or punching mechanism and the paper stepping mechanism;

Fig. 3 is a perspective view of the signal pickup mechanism and the tape takeup roll; and

Fig. 4 is a fragmentary elevation, partly in sec-

tion of the feed screw of the pickup mechanism.

In the embodiment of the invention described and illustrated the selecting signals are created by a dial 10. Since the phonograph is intended for the accommodation of one hundred recordings it is preferred to have two dial actuations for each recording. The dial can thus be operated to select recordings from 00 to 99. If the No. 0 is dialed three impulses are created, if the No. 1 is dialed 4 impulses are created and if No. 9 is dialed 12 impulses are created. When the dial is thus actuated the printing or punching mechanism 11 applies 3, 4 or 12 space perforations in the transverse direction upon a broad tape 12. 15 After each punching operation the tape 12 is fed to the right as viewed in Fig. 1 a short distance by the paper feed mechanism 13 so that the various trains of perforations are spaced in the longitudinal direction of the tape. The tape 12 may be paper tape of the type used in adding machines and may be approximately two or three inches wide, the machine being preferably adapted to take a standard tape which can be purchased in rolls. After two trains of perforations, corresponding to an individual recording, have been applied to the tape the motor 14 goes into operation to feed the tape to the right as viewed in Fig. 1 until the first train of impulses is brought into cooperative relation with the signal pickup mechanism 15. The tape 12 then stops and the mechanism 15 picks up the first train of impulses and supplies the same to the stepping mechanism 16. The stepping mechanism 16 and the associated elements may be substantially similar to those described in copending application Ser. No. 505,776, filed October 11, 1943, by Mahlon W. Kenney and Herman G. Jensen, or the copending application Ser. No. 561,986 (Case 6) filed by the same applicants on November 4, 1944. These elements will therefore be very briefly described herein. The stepping mechanism 16 on its first actuation carries an actuator 17 a corresponding number of large steps from its initial position. The second operation of the stepping means 16 carries the actuator 17 around a corresponding number of small steps. The actuator 17 is arranged to cooperate with any of one hundred selector bars 18 which are arranged in arcuate or circular path. The bars 18 are equally spaced and the large steps of the stepping mechanism 16 are equal to ten spaces of the bars 18. The small steps effected by the stepping mechanism 16 are equal to single spacings of the bars 18. The actuator 17 is arranged so that it registers with one of the bars 18 and consequent-

ly two stepping operation of the mechanism 16 brings the actuator 17 into alignment with the bar 18 corresponding to the two trains of impulses. After the actuator 17 has been thus located by two trains of impulses received by the stepping mechanism 16 the electromagnet 19 is energized moving the actuator 17 upwardly and displacing the bar 18 upwardly. Upward displacement of a bar 18 upwardly energizes a relay 20 which closes a switch 21 to put the phonograph motor 22 into operation. The operation of the motor 22 puts the selecting mechanism of the phonograph into operation and closes a switch 23 in parallel with the switch 21 so that the motor 22 remains in operation until the selected recording has been completely reproduced and the switch 23 is again open, notwithstanding that the switch 21 may be opened before the complete reproduction of the recording, as will hereinafter be more fully described. The record changing mechanism drives a disc 24 through at least one revolution so that a projection 25 thereon engages the bar 18 which is upwardly displaced. This engagement arrests the disc 24 which is frictionally driven. The arrested position of the disc 24 determines the recording which is reproduced by the phonograph. After the recording has been determined the electromagnet 26 is automatically energized momentarily so that the plunger 27 adjacent the abutment 25 is moved downwardly to return the arresting bar 18 to its normal position. The relay 20 is deenergized but the phonograph motor 22 continues to operate since the switch 23 is closed. In the event that the operator has made at least two selections the pickup mechanism 15 goes into operation to displace the bar 18 corresponding to the second selection. When any bar 18 is displaced the pickup mechanism is rendered inoperative. Thus the normal operation of the phonograph is that a recording is being reproduced and the bar 18 for the next recording is displaced. The remaining selection signals are stored in the tape between the punching mechanism 11 and the pickup mechanism 15. Normally the portion of the tape bearing the signals may accommodate itself in a depending loop as shown in dot and dash lines at 28 in Fig. 1. Since a large number of selections may be recorded on a relatively short piece of tape the accommodation of the loop 28 is very easily provided. Since the tape is quite broad a large loop 28 can be accommodated without any tendency to snarling.

The supply of tape is in the form of a roll 29 rotatably mounted on a spindle 30. A brake 31 bears against the roll so as to keep the paper taut. The tape 12 passes from the roll through guides 32 on the punching mechanism, through feed rolls 33 of the paper feed mechanism 13 between the contacts 34 and 35 of the pickup mechanism 15 to the takeup drum 36 which is driven in clockwise direction as viewed in Fig. 1 by a motor 14 through suitable gear reduction. Idler rolls are provided for guiding the paper at intermediate points.

Power is supplied to the unit by the primary 37 of a transformer 38. A secondary 39 of the transformer provides filament current to two grid controlled "thyatron" tubes 40 and 41. A secondary 42 is connected to the plate of the "thyatron" 40 and to the solenoid 43 which operates the punching mechanism. The other side of this solenoid is grounded as is the cathode of the "thyatron" 40. A secondary 44 supplies A. C. current to the line 45. A secondary 46 supplies

current to the filament cathode of the push pull rectifying tube 47. The anodes of the tubes 47 are connected to the ends of the secondary 48, the center tap of which is grounded through a limiting resistor 49. The output of the rectifier 47 is filtered by the filter 50 and the direct current is supplied to the line 51. The secondary 52 is connected to the stepping unit 16 by a line 53 and to the plate of the "thyatron" 41. The other line 54 connected to the stepping unit 16 is grounded as is the cathode of the "thyatron" 41.

The dial 10 operates the impulse switch 55. One side of this switch is grounded and the other is connected to the control grid of the "thyatron" 40. This grid is negatively biased by a line 56 through suitable limiting resistors. When the dial is operated and released the switch 55 closes a corresponding number of times effectively grounding the control grid of the thyatron 40 with the result that a corresponding number of actuating impulses is supplied to the solenoid 43. During the repeated energization of the solenoid 43 the switch 57 is repeatedly closed. One side of this switch is grounded, its other side being connected to the slow release relay 58 which is also connected to the D. C. line 51. Consequently the relay 58 remains energized during the reception of a train of impulses by the solenoid 43. The relay 58 controls the two way switch 59 and the normally closed switch 60. One contact of the switch 59 is connected to the D. C. line 51. When the relay 58 is energized the movable pole of the switch 59 engages this contact. This movable pole is connected to a relatively large condenser 61 the other side of which is grounded. Consequently when the relay 58 is energized the condenser 61 is connected to the D. C. line 51 and is charged. When the relay 58 is deenergized at the end of a train of impulses the movable pole engages the other contact of the switch 59 which is connected to the relay 62 so that the condenser is discharged through the relay 62, the other side of which is grounded. It may be here noted that during creation of impulses by the dial 10 the switch 60 is open and the electromagnet 63 is deenergized. The discharge of the condenser 61 through the relay 62 closes the switches 64 and 65. One side 50 of each of these switches is connected to the A. C. line 45. The other side of the switch 64 is connected to the reset magnet 66 of the punching unit 11 and to the paper feed magnet 67. The other sides of these magnets are grounded. The 55 other side of the switch 65 is connected to the electromagnet 68, the other side of which is grounded. The armature 69 of the electromagnet 68 cooperates with a toothed counting wheel 70. This armature extends through a window 71 so that its movement is limited to effect the displacement of the counting wheel 70 one tooth in the counterclockwise direction as viewed in Fig. 1. A spring pressed detent 72 holds the wheel 70 in the position into which it is actuated. 60 In its normal position an abutment 73 on the wheel 70 engages a stationary abutment 74. An abutment 75 on the wheel 70 normally holds a switch 76 open. When the wheel 70 is displaced in counterclockwise direction two or more tooth 65 spaces from its normal position the switch 76 closes.

The wheel 70 is moved two teeth at a time in the clockwise direction by the armature 77 of a relay 78 which is connected in parallel with the 75 electromagnet 19. Consequently each time that a

bar 18 is displaced the wheel 10 is displaced two teeth in the clockwise direction as viewed in Fig. 1. The armature 77 projects through a window 79 which limits its movement of the wheel 10 to two teeth.

One side of the switch 76 is grounded. Its other side is connected to one side of a normally closed switch 80 which is opened when the relay 20 is energized. The other side of the switch 80 is connected to one side of a switch 81, to one terminal of the motor 14 and to one side of a normally open switch 82. The other side of the switch 82 is grounded. The other side of the switch 81 is connected to one side of the switch 80, the other side of which is connected to the electromagnet 63. The other side of the electromagnet 63 is connected to one side of the normally closed switch 83. The other side of the switch 83 is connected to the other terminal of the motor 14 and to the A. C. line 45.

The magnet 84 on the pickup unit has one side grounded. The other side is connected to one side of a normally open switch 85 and to one side of a normally open switch 86. The other sides of these switches are connected to the A. C. line 45. One of the pickup contacts 35, is grounded. The other pickup contact 34 is connected through a normally closed switch 87 to a sensitive relay 88 which is connected to the D. C. line 51. The relay 88 closes each time that the contacts 34 and 35 engage through a perforation in the tape 12. The relay 88 actuates two normally open switches 89 and 90. One side of each of these switches is grounded. The other side of the switch 90 is connected through a slow release relay 91 to the D. C. line 51. The other side of the switch 89 is connected to the control grid of the thyratron 41. This grid is negatively biassed by a line 92 through a suitable limiting resistor. It will thus be seen that each time the switch 89 closes the control grid of the thyratron 41 is effectually grounded so that an impulse is transmitted through the lines 53 and 54 to the stepping mechanism 16.

The punching or printing mechanism is shown in Fig. 2. It comprises a stationary frame 93 which carries a rack 94. The frame 93 provides guides 95 which support a carriage 96 for horizontal sliding movement. The carriage 96 is largely broken away in Fig. 2 to disclose the mechanism, but it will be understood that the carriage is slidably supported so that the punch 97 may be moved inwardly that is to the right as viewed in Fig. 2 across the tape 12. The carriage 96 carries the solenoid 43 and the electromagnet 66. The armature of the solenoid 43 is pivotally connected to a lever 98 which is pivotally mounted on the carriage 96. A spring 99 biasses the armature of the solenoid upwardly. The forward end of the lever 98 engages the punch 97 so that each time the solenoid 43 is energized the punch 97 is forced downwardly through the tape 12 making a perforation therein. The lower end of the punch 97 is adapted to pass through aligned openings in the guides 32. The punch 97 is normally biassed upwardly by a spring 100. The other end of the lever 98 carries a pivoted dog 101 which normally engages a ratchet wheel 102 rigidly mounted on a pinion 103 mounted on the carriage 96 and cooperating with the rack 94. A holding dog 104 pivotally supported on the carriage 96 engages the ratchet wheel 102. Each time the solenoid 43 is energized the dog 101 rises and each time the solenoid 43 is deenergized the spring 99 moves the

dog 101 downwardly again so that it carries the ratchet wheel 102 one tooth in the clockwise direction as viewed in Fig. 2. The pinion 103 is rotated one step so that the carriage 96 is moved inwardly one step. Thus as a series of impulses is received by the solenoid 43 the carriage 96 moves inwardly step by step applying perforations to the tape 12 along a transverse line. The first perforation is made by the punch 97 in its normal or initial position near one edge of the tape and the spaces effected by the dog 101 are arranged so that the maximum number of perforations, in the present instance 12, can be applied across the tape. The carriage 96 is biassed towards its normal position by a spring 105 connected to the carriage and to the frame 93. The armature of the electromagnet 66 is connected to an unlatching bar 106. The bar 106 carries projections which are adapted to engage the tail of the dog 104 and a pin 107 carried by the dog 101. When the electromagnet 66 is energized after the train of impulses had been received by the solenoid 43 the bar 106 is moved towards the paper so that its projections raise the dogs 101 and 104 away from the ratchet wheel 102. The carriage 96 is now free so that it is returned to its normal position by the spring 105. The carriage 96 carries the switch 57. This switch is engaged by the lever 98 in such manner that each time the solenoid 43 is energized the switch 57 closes.

The paper feed mechanism also shown in Fig. 2 comprises the two rollers 33. These rollers rigidly carry meshing gears 108. The lower gear 108 rigidly carries a ratchet wheel 109 which is held against rotation in the counterclockwise direction by a detent 110. The ratchet wheel 109 is adapted to be stepped in the clockwise direction by means of a dog 111 carried on a pivoted lever 112. The lever 112 is biassed upwardly against a stop (not shown) by a spring 113. Each time the electromagnet 67 is energized, that is after each dialed train is received by the punching mechanism 13, the lever 112 is moved downwardly so that the dog 111 moves the paper one step towards the right as viewed in Fig. 1.

The paper takeup roll 36 is driven by the motor 14 through a slipping clutch 114. The roll 36 rigidly carries a ratchet wheel 115 which is normally engaged by a dog 116. This dog is adapted to be raised away from the ratchet wheel 115 by the electromagnet 63 against the influence of a spring 117. When the motor 14 is running and the electromagnet 63 is energized the takeup roll 36 is driven.

The contacts 34 and 35 are mounted on a carriage 118 which is mounted for sliding movement in the transverse direction of the tape on bars 119 carried by a frame 120. The carriage 118 is normally located with the contacts 34 and 35 in alignment with the punch 97 so that as the tape is fed to the right by the pickup drum 36 the contacts 34 and 35 engage through the first of a train of perforations in the tape. This engagement effects the deenergization of the magnet 63 so that the dog 116 arrests the roll 36 leaving the line of perforations in alignment with the contacts 34 and 35. In its normal position the carriage 118 holds the switches 85 and 82 open and the switch 83 closed, these switches being mounted on the frame 120. When the carriage 118 starts to move across the paper tape switches 85 and 82 close and switch 83 opens. The traverse of the carriage 118 is effected by the screw 121 which is rotatably mounted on the frame 120 in

the transverse direction of the tape. The screw 121 is provided with a helical groove 122 which is engaged by a tooth 123 slidably mounted on the carriage 118. The tooth 123 is biased towards the screw 121 by a spring 124. An upwardly directed arm 125 integral with the tooth 123 controls the switch 87 which is mounted on the carriage 118. When the tooth 123 is in the groove 122 the switch 87 is closed. The upper end of the arm 125 carries a recess 126. A dog 127 pivotally mounted on the carriage 118 is adapted to enter the recess 126 under the influence of its spring 128 when the tooth 123 is moved radially away from the screw 121. When the tooth is thus moved radially away from the screw 121 the switch 87 is opened and it is locked open by the dog 127. The radial movement of the tooth 123 is effected at the end of the inward traverse of the frame 118 by the cam-shaped portion 129 of the groove 122 best shown in Fig. 4. At the end of the traverse of the carriage 118 the tooth 123 rises on the cam-shaped portion 129, the switch 87 is opened and the tooth 123 is located out of the groove 122. The carriage 118 is biased towards its initial position by means of a spring 130 so that when the tooth 123 is latched out by the dog 127 the carriage 118 returns to its initial position. The carriage 118 carries an electromagnet 131 which is adapted, when energized, to attract the tail of the dog 127. One side of the magnet is connected to the AC line 45. The other side of the magnet is connected to a contact 136 which is adapted to engage a grounded contact 137. The contacts 136 and 137 are in alignment with the contacts 34 and 35 in the longitudinal direction of the tape and they are located to the right of the contacts 34 and 35 by a distance less than the distance through which the paper tape is stepped by the paper feed mechanism 13. Consequently when the contacts 34 and 35 are scanning a row of perforations, the contacts 136 and 137 are separated by the tape and the electromagnet 131 remains deenergized. After the contacts 34 and 35 have scanned a row of perforations and returned to their initial position the switch 87 is locked open. When the tape begins to move the contacts 34 and 35 are separated and the first of the scanned openings reaches the contacts 136 and 137 so that the electromagnet 131 is energized and the dog 127 unlatches the tooth 123 so that it is biased towards the screw 121. When the screw 121 is again put into rotation the tooth 123 drops into the groove 122 and the switch 87 is again closed so that the circuit of the contacts 34 and 35 is conditioned for cooperation with the next row of perforations.

The screw 121 is driven from the motor 14 by means of a sprocket chain 132 and a friction clutch 133. The screw 121 rigidly carries a toothed wheel 134 which is normally engaged by a dog 135 to prevent rotation of the screw. The tail of the dog 135 is arranged to be attracted by the electromagnet 84 mounted on the frame 120 so that when this electromagnet is energized and the motor 14 is in operation the screw 121 is driven.

The operation will now be described in case that the operator dials two numbers corresponding to a definite recording such as No. 64. The operator dials 6 and when he releases the dial the switch 55 closes nine times. The "thyatron" 40 flashes nine times and the solenoid 43 is energized nine times. The punch 97 punches nine equally spaced holes in a line across the tape 12. During these nine punching operations the switch 57 closes

nine times and the relay 58 remains energized. While the relay 58 is energized the switch 60 is open and the takeup roll 36 remains stationary because the magnet 63 is deenergized. The condenser 61 is charged and at the end of the train of impulses it becomes discharged through the relay 62. The switches 64 and 65 close momentarily with the result that the magnets 66, 67 and 68 are momentarily energized. The wheel 70 is moved one tooth in the counterclockwise direction. The dogs 101 and 104 of the punching mechanism are raised from the ratchet wheel 102 so that the spring 105 returns the carriage 96 to its initial position. The energization of the magnet 67 moves the tape at the punching mechanism 11 one step to the right as viewed in Fig. 1. The switch 76 remains open since the wheel 70 has merely moved one tooth in the counterclockwise direction.

When the operator dials the No. 4 the same operation is repeated and seven perforations are made across the tape. In this case the second energization of the relay 68 moves the wheel 70 the second tooth in the counterclockwise direction as viewed in Fig. 1 closing the switch 76. When the switch 76 closes the circuit of the motor 14 is completed and the electromagnet 63 is energized. The motor 14 consequently drives the takeup roll 36 but the screw 121 is not driven because the electromagnet 84 is not energized. The circuit of the motor is completed through switch 76, switch 80, motor 14 to A. C. line 45. The circuit of the magnet 63 is completed through switch 76, switch 80, switch 84, switch 60, electromagnet 63, switch 83 to A. C. line 45. The paper is consequently driven to the right as viewed in Fig. 1 until the first perforation of the first train permits engagement between contacts 34 and 35. This engagement energizes the relay 88 through the closed switch 87 closing the contacts 89 and 90 and energizing the relay 91. This opens the switch 84 and closes the switch 86 energizing the magnet 84 and deenergizing the magnet 63. Deenergization of the magnet 63 arrests the drive of the roll 36 so that the paper tape is stationary with the contacts 34 and 35 engaged through the first perforation of the first train. The circuit of the motor 14 is maintained and since the magnet 84 is energized the screw 50 121 is driven and the carriage 118 is moved in the transverse direction of the paper so that the relay 88 is energized nine times. The closing of the switch 89 nine times causes the thyatron 41 to flash nine times and nine stepping impulses 55 are supplied to the stepping mechanism 16 moving the actuator 17 nine steps each corresponding to ten times the spacing of the bars 18. When the carriage 118 started its transverse movement switches 85 and 82 closed and the switch 83 opened. The closed switches 85 and 60 82 complete independent circuits for the magnet 84 and the motor 14 so that the drive of the screw 121 is maintained and the drive of the tape by the roll 36 is prevented until the carriage 118 has made its full travel and has returned to its initial position. When the carriage 118 has made its full travel across the paper the switch 87 is locked open and during the return movement of the carriage 118 the circuit of the relay 88 is open 70 and no impulses are transmitted to or by the thyatron 41.

The return of the carriage 118 to its normal position opens the switches 82 and 85 and closes the switch 83. The electromagnet 84 is deenergized so that the drive of the screw 121 is ter-

minated. The circuit of the motor 14 through the closed switches 76 and 80 is maintained so that the motor continues to operate. The electromagnet 63 is energized so that the drum 36 is driven. The movement of the paper tape brings the first of the train of perforations just scanned by the contacts 34 and 35 into alignment with the contacts 136 and 137 so that the electromagnet 131 is energized releasing the dog 127 and closing the switch 81. Continued movement 10 of the paper tape brings the next train of perforations, that is the seven perforations, into alignment with the contacts 34 and 35 with the result that the drive of the paper is terminated by the deenergization of the magnet 63 and the screw 121 is driven owing to the energization of the electromagnet 84. Consequently seven impulses are supplied to the stepping mechanism 16 and the actuator 17 is located below the bar 18 corresponding to selection No. 64. The electromagnets 19 and 78 are thereupon energized with the result that the corresponding bar 18 is actuated and the switch 76 is opened thus terminating the operation of the motor 14. The phonograph motor 22 is put into operation by the closing of the switch 21 and the phonograph operates until the recording is completely reproduced and the switch 23 is opened. As has been heretofore explained the electromagnet 26 returns the actuated bar 18 to its normal position and the actuator 17 returns to its initial position.

If the operator dials up two selections by four operations of the dial 10, four rows of perforations are applied transversely of the broad tape 12. At the end of the second dialing the switch 76 closes and the motor 14 starts drawing the paper tape to the right as viewed in Fig. 1 until the first row of perforations becomes aligned with the contacts 34 and 35. In the event that the third dialing is made while the tape is moving 40 the drive of the tape is interrupted by the opening of the switch 60 so that the tape is always at rest during a punching operation. After the dialing the movement of the tape by the motor 14 is resumed until the first row of perforations is aligned with the contacts 34 and 35, whereupon the drive of the paper is terminated and the screw 121 is put into operation to transmit the corresponding number of impulses to the stepping mechanism 16. The tape moves again to bring the second row of perforations into alignment with the contacts 34 and 35 and again the corresponding number of impulses is transmitted to the stepping mechanism 16. The electromagnets 19 and 78 are then energized and the corresponding bar 18 is displaced so that the motor 22 is put into operation to reproduce the first selected recording. Displacement of the bar 18 energized the relay 20 so that the switch 80 is opened and the circuits of the motor 14 and the relay 63 are broken. Consequently the drive of the pickup roller 36 is terminated as long as a pin 18 is displaced. It is to be noted that the energization of the magnet 78 does not open the switch 76 since the wheel 70 has been displaced four teeth in the counterclockwise direction by the four dialing operations. When the first selection has been determined the corresponding bar 18 is returned to its initial position, the switch 80 closes and the motor 14 is put into operation to pick up signals from the two trains corresponding to the second selection with the result that the bar 18 corresponding to the second selection is displaced. The wheel 70 is moved back two teeth when the second bar 18 is displaced so that the

motor 14 is rendered inoperative. After the first recording is reproduced the abutment 25 on the disc 24 cooperates with the displaced bar to determine the second recording and this bar is returned to its normal position. The phonograph motor 22 continues to operate until the second selected recording is fully reproduced whereupon the operation of the phonograph is completely terminated by the opening of the switch 23.

If the operator makes a larger number of selections, for example five, by dialing ten times, the operation is the same except that the switch 76 does not become closed until the five corresponding bars 18 have been displaced. A typical operating condition is that when the second selection is being reproduced the bar 18 of the third selection is displaced and the wheel 70 is four teeth away from its position for closing the switch 76. Consequently the phonograph operates to play the five recordings in the order in which the selections were made.

Thus the stepping mechanism 16 may be arranged for operation with one train of impulses and in this case the counter 70 is arranged so that one tooth movement from normal position closes the switch 76. The relay 78 is modified so that it returns the wheel one tooth on each actuation. In the case three trains of impulses are employed, the stepper 16 must require three trains to make a selection. The relay 78 must return the wheel 70 three teeth each time it is energized, and the switch 76 must be arranged so that it will not close until the wheel 70 has been moved three teeth from normal position by three energizations of the relay 68.

Although the invention has been described in connection with the specific details of a preferred embodiment thereof, it must be understood that such details are not intended to be limitative of the invention except in so far as set forth in the accompanying claims.

I claim:

1. A multiselective phonograph having a plurality of displaceable members each corresponding to an individual recording, stepping mechanism responsive to impulses to displace any of said members, a broad tape, a punching mechanism arranged to be actuated by a series of impulses to punch a series of openings in a transverse direction across said tape, means for moving said tape longitudinally, a pickup means through which said tape passes, means associated with said pickup means for arresting said tape when a series of openings is aligned with said pickup means, means for moving said pickup means transversely over a series of openings in the tape to pick up a series of impulses, and means for supplying the picked up impulses to the stepping means.

2. A multiselective phonograph having a plurality of displaceable members each corresponding to an individual recording, stepping mechanism responsive to impulses to displace any of said members, a broad tape, a punching mechanism arranged to be actuated by a series of impulses to punch a series of openings in a transverse direction across said tape, means for moving said tape longitudinally, a pickup means through which said tape passes, means associated with said pickup means for arresting said tape when a series of openings is aligned with said pickup means, means for moving said pickup means transversely over a series of openings in the tape to pick up a series of impulses, means for supplying the picked up impulses to the

stepping means, and means controlled by any displaceable member in displaced condition, for rendering said tape moving means inoperative.

3. A multiselective phonograph having a plurality of displaceable members each corresponding to an individual recording, stepping mechanism responsive to impulses to displace any of said members, a broad tape, a punching mechanism arranged to be actuated by a series of impulses to punch a series of openings in a transverse direction across said tape, means for moving said tape longitudinally, a pickup means through which said tape passes, means associated with said pickup means for arresting said tape when a series of openings is aligned with said pickup means, means for moving said pickup means transversely over a series of openings in the tape to pick up a series of impulses, means for supplying the picked up impulses to the stepping means, a counter associated with said punching means and said pickup means to be actuated thereby in opposite directions, and cooperating means associated with said counter and with each displaceable member for rendering said tape moving means operative and inoperative.

4. A multiselective phonograph having a plurality of displaceable members each corresponding to an individual recording, stepping mechanism responsive to impulses to displace any of said members, a broad tape, a punching mechanism arranged to be actuated by a series of impulses to punch a series of openings in a transverse direction across said tape, means for stepping said tape longitudinally after a series of openings is punched whereby any desired number of series may be punched, a pickup means through which said tape passes, means for moving said tape through said pickup means, means associated with said pickup means for arresting said tape when a series of openings is aligned with said pickup means, means for moving said pickup means transversely over a series of openings in the tape to pick up a series of impulses, and means for supplying the picked up impulses to the stepping means.

5. A multiselective phonograph having a plurality of displaceable members each corresponding to an individual recording, stepping mechanism responsive to impulses to displace any of said members, a broad tape, a punching mechanism arranged to be actuated by a series of impulses to punch a series of openings in a transverse direction across said tape, means for stepping said tape longitudinally after a series of openings is punched whereby any desired number of series may be punched, a pickup means through which said tape passes, means for moving said tape through said pickup means, means associated with said pickup means for arresting said tape when a series of openings is aligned with said pickup means, means for moving said pickup means transversely over a series of openings in the tape to pick up a series of impulses, means for supplying the picked up impulses to the stepping means, and means controlled by any of said displaceable members in displaced condition for rendering said tape moving means ineffective.

6. A multiselective phonograph having a plurality of displaceable members each corresponding to an individual recording, stepping mechanism responsive to impulses to displace any of said members, a broad tape, a punching mechanism arranged to be actuated by a series of impulses to punch a series of openings in a trans-

verse direction across said tape, means for stepping said tape longitudinally after a series of openings is punched whereby any desired number of series may be punched, a pickup means through which said tape passes, means for moving said tape through said pickup means, means associated with said pickup means for arresting said tape when a series of openings is aligned with said pickup means, means for moving said pickup means transversely over a series of openings in the tape to pick up a series of impulses, means for supplying the picked up impulses to the stepping means, a counter associated with said punching means and said pickup means to be actuated thereby in opposite directions, and cooperating means associated with said counter and with each displaceable member for rendering said tape moving means operative and inoperative.

20 7. A multiselective phonograph having a plurality of displaceable members each corresponding to an individual recording, stepping mechanism responsive to impulses to displace any of said members, a broad tape, a punching mechanism arranged to be actuated by a series of impulses to punch a series of openings in a transverse direction across said tape, means for stepping said tape longitudinally after a series of openings is punched whereby any desired number of series may be punched, a pickup means through which said tape passes, means for moving said tape through said pickup means, means associated with said pickup means for arresting said tape when a series of openings is aligned with said pickup means, means for moving said pickup means transversely over a series of openings in the tape to pick up a series of impulses, means for supplying the picked up impulses to the stepping means, a counter associated with said punching means and said pickup means to be actuated thereby in opposite directions, cooperating means associated with said counter and with each displaceable member for rendering said tape moving means operative and inoperative, and means associated with said punching mechanism for preventing operation of the tape moving means during the punching of openings.

8. A multiselective phonograph having a plurality of displaceable members each corresponding to an individual recording, stepping mechanism responsive to impulses to displace any of said members, automatic means for returning each displaced displaceable member to normal position after it has determined the recording to be played, a broad tape, a punching mechanism arranged to be actuated by a series of impulses to punch a series of openings in a transverse direction across said tape, means for stepping said tape longitudinally after a series of openings is punched whereby any desired number of series may be punched, a pickup means through which said tape passes, means for moving said tape through said pickup means, means associated with said pickup means for arresting said tape when a series of openings is aligned with said pickup means, means for moving said pickup means transversely over a series of openings in the tape to pick up a series of impulses, means for supplying the picked up impulses to the stepping means, a counter associated with said punching means and said pickup means to be actuated thereby in opposite directions, and cooperating means associated with said counter and with each displaceable member for rendering said tape moving means operative and inoperative.

75 70 65 60 55 50

9. A multiselective phonograph having a plurality of displaceable members each corresponding to an individual recording, stepping mechanism responsive to impulses to displace any of said members, automatic means for returning each displaced displaceable member to normal position after it has determined the recording to be played, a manually operable impulser for supplying impulses to said stepping mechanism, a broad tape, a punching mechanism arranged to be actuated by a series of impulses to punch a series of openings in a transverse direction across said tape, means for stepping said tape longitudinally after a series of openings is punched whereby any desired number of series may be punched, a pickup means through which said tape passes, a motor, means driven by said motor for moving said tape through said pickup means, means associated with said pickup means for arresting said tape when a series of openings is aligned with said pickup means, means for moving said pickup means transversely over a series of openings in the tape to pick up a series of impulses, means for supplying the picked up impulses to the stepping means, a counter associated with said punching means and said pickup means to be actuated thereby in opposite directions, cooperating means associated with said counter and with each displaceable member for rendering said tape moving means operative and inoperative, and means associated with said punching mechanism for preventing the operation of the tape moving means during the punching of openings.

10. A multiselective phonograph having a plurality of displaceable members each corresponding to an individual recording, stepping mechanism responsive to impulses to displace any of said members, automatic means for returning each displaced displaceable member to normal position after it has determined the recording to be played, a manually operable impulser for supplying impulses to said stepping mechanism, a broad tape, a punching mechanism arranged to be actuated by a series of impulses to punch a series of openings in a transverse direction across said tape, means for stepping said tape longitudinally after a series of openings is punched whereby any desired number of series may be punched, a pickup means through which said tape passes, means for moving said tape through said pickup means, means associated with said pickup means for arresting said tape when a series of openings is aligned with said pickup means, means for moving said pickup means transversely over a series of openings in the tape to pick up a series of impulses, a motor for driving said pickup moving and tape moving means alternately, means for supplying the picked up impulses to the stepping means, a counter associated with said punching means and said pickup means to be actuated thereby in opposite directions, and cooperating means associated with said counter and with each displaceable member for rendering said motor operative and inoperative.

11. A multiselective phonograph having a plurality of displaceable members each corresponding to an individual recording, stepping means responsive to a definite plurality of series of impulses to displace any of said members, a broad tape, a punching mechanism arranged to be actuated by a series of impulses to punch a series of openings in a transverse direction across said tape, means for moving said tape longitudinally, a pickup means through which said tape passes,

means associated with said pickup means for arresting said tape when a series of openings is aligned with said pickup means, means for moving said pickup means transversely over a series of openings in the tape to pick up a series of impulses, means for supplying the picked up impulses to the stepping means, means responsive to said definite plurality of series of impulses supplied to said punching mechanism to render said tape moving means and pick-up means operative, and means controlled by a displaced displaceable member for rendering said tape moving means and said pickup means inoperative.

12. A multiselective phonograph having a plurality of displaceable members each corresponding to an individual recording, stepping means responsive to a definite plurality of series of impulses to displace any of said members, a broad tape, a punching mechanism arranged to be actuated by a series of impulses to punch a series of openings in a transverse direction across said tape, means for moving said tape longitudinally, a pickup means through which said tape passes, means associated with said pickup means for arresting said tape when a series of openings is aligned with said pickup means, means for moving said pickup means transversely over a series of openings in the tape to pick up a series of impulses, a counter operatively associated with said punching mechanism to be actuated one step each time the punching mechanism punches a series of openings, means for supplying the picked up impulses to the stepping means, means controlled by said counter after it has been actuated a number of times equal to said definite plurality of series of impulses to render said tape moving means and pickup means operative, and means controlled by a displaced displaceable member for rendering said tape moving means and said pickup means inoperative.

13. A multiselective phonograph having a plurality of displaceable members each corresponding to an individual recording, stepping means responsive to a definite plurality of series of impulses to displace any of said members, a broad tape, a punching mechanism arranged to be actuated by a series of impulses to punch a series of openings in a transverse direction across said tape, means for moving said tape longitudinally, a pickup means through which said tape passes, means associated with said pickup means for arresting said tape when a series of openings is aligned with said pickup means, means for moving said pickup means transversely over a series of openings in the tape to pick up a series of impulses, a counter operatively associated with said punching mechanism to be actuated one step each time the punching mechanism punches a series of openings, means for supplying the picked up impulses to the stepping means, a switch arranged to be actuated by said counter after it has been actuated said definite plurality of times, means controlled by said switch for rendering said tape moving means and pickup means operative and a switch controlled by a displaced displaceable member for rendering said tape moving means and said pickup means inoperative.

14. A multiselective phonograph having a plurality of displaceable members each corresponding to an individual recording, stepping means responsive to a definite plurality of series of impulses to displace any of said members, a broad tape, a punching mechanism arranged to be actuated by a series of impulses to punch a series of openings in a transverse direction across said

tape, means for moving said tape longitudinally, a pickup means through which said tape passes, means associated with said pickup means for arresting said tape when a series of openings is aligned with said pickup means, means for moving said pickup means transversely over a series of openings in the tape to pick up a series of impulses, means for supplying the picked up impulses to the stepping means, means responsive to said plurality of series of impulses supplied to said punching mechanism to render said tape moving means and pickup means operative, means controlled by a displaced displaceable member for rendering said tape moving means and said pickup means inoperative, and automatic means for returning said displaceable member after it has predetermined the reproduction of the corresponding recording.

15. A multiselective phonograph having a plurality of displaceable members each corresponding to an individual recording, stepping means responsive to a definite plurality of series of impulses to displace any of said members, a broad tape, a punching mechanism arranged to be actuated by a series of impulses to punch a series of openings in a transverse direction across said tape, means for moving said tape longitudinally, a pickup means through which said tape passes, means associated with said pickup means for arresting said tape when a series of openings is aligned with said pickup means, means for moving said pickup means transversely over a series of openings in the tape to pick up a series of impulses, a counter means operatively associated with said punching mechanism to be actuated one step each time the punching mechanism punches a series of openings, means for supplying the picked up impulses to the stepping means, means controlled by said counter after it has been actuated a number of times equal to said definite plurality of series of impulses to render said tape moving means and pickup means operative, means controlled by a displaced displaceable member for rendering said tape moving means and said pickup means inoperative, and automatic means for returning said displaceable member after it has predetermined the reproduction of the corresponding recording.

16. A multiselective phonograph having a plurality of displaceable members each corresponding to an individual recording, stepping means responsive to a definite plurality of series of impulses to displace any of said members, a broad tape, a punching mechanism arranged to be actuated by a series of impulses to punch a series of openings in a transverse direction across said tape, means for moving said tape longitudinally, a pickup means through which said tape passes, means associated with said pickup means for arresting said tape when a series of openings is aligned with said pickup means, means for moving said pickup means transversely over a series of openings in the tape to pick up a series of impulses, a counter means operatively associated with said punching mechanism to be actuated one step each time the punching mechanism punches a series of openings, means for supplying the picked up impulses to the stepping means, means controlled by said counter after it has been actuated a number of times equal to said definite plurality of series of impulses to render said tape moving means and pickup means operative, means controlled by a displaced displaceable member for

rendering said tape moving means and said pickup means inoperative, automatic means for returning said displaceable member after it has predetermined the reproduction of the corresponding recording, and means associated with said automatic means for returning said counter by said definite number of steps each time a displaceable member is returned.

17. A multiselective phonograph having a plurality of displaceable members each corresponding to an individual recording, stepping means responsive to a plurality of series of impulses to displace any of said members, a broad tape, a punching mechanism arranged to be actuated by a series of impulses to punch a series of openings in a transverse direction across said tape, means for moving said tape longitudinally, a pickup means through which said tape passes, means associated with said pickup means for arresting said tape when a series of openings is aligned with said pickup means, means for moving said pickup means transversely over a series of openings in the tape to pick up a series of impulses, a counter operatively associated with said punching mechanism to be actuated one step each time the punching mechanism punches a series of openings, means for supplying the picked up impulses to the stepping means, a switch arranged to be actuated by said counter after it has been actuated said definite plurality of times, means controlled by said switch for rendering said tape moving means and pickup means operative, a switch controlled by a displaced displaceable member for rendering said tape moving means and said pickup means inoperative, and automatic means for returning said displaceable member after it has predetermined the reproduction of the corresponding recording.

18. A multiselective phonograph having a plurality of displaceable members each corresponding to an individual recording, stepping means responsive to a plurality of series of impulses to displace any of said members, a broad tape, a punching mechanism arranged to be actuated by a series of impulses to punch a series of openings in a transverse direction across said tape, means for moving said tape longitudinally, a pickup means through which said tape passes, means associated with said pickup means for arresting said tape when a series of openings is aligned with said pickup means, means for moving said pickup means transversely over a series of openings in the tape to pick up a series of impulses, a counter operatively associated with said punching mechanism to be actuated one step each time the punching mechanism punches a series of openings, means for supplying the picked up impulses to the stepping means, a switch arranged to be actuated by said counter after it has been actuated said definite plurality of times, means controlled by said switch for rendering said tape moving means and pickup means operative, a switch controlled by a displaced displaceable member for rendering said tape moving means and said pickup means inoperative, automatic means for returning said displaceable member after it has predetermined the reproduction of the corresponding recording, and means associated with said automatic means for returning said counter by said definite number of steps each time a displaceable member is returned.

MAHLON W. KENNEY.
